BEER FOAM REMOVER AND ADVERTISING DEVICE

Robert J. Campbell, Sacramento, Calif.

Application November 25, 1936, Serial No. 112,783

5 Claims. (Cl. 225—6)

This invention relates to certain new and useful improvements in beer foam remover and advertising device.

A primary object of the invention is to provide a device adapted for attachment to a spigot or faucet for the dispensing of beer and including a blade edge over which the upper end of a glass may be moved and in proximity of the spigot or faucet for the removal of excess foam from the beer in the glass and further including an upstanding arm that projects above the counter or shelf that supports the spigot or faucet for the display of an advertising card or the like.

With the above and other objects in view that will become apparent as the nature of the invention is better understood, the same consists in the novel form, combination and arrangements of parts hereinafter more fully described, shown in the accompanying drawing and claimed.

20 In the drawing:—

Figure 1 is a fragmentary side elevational view of a counter or bar having a valve controlled spigot carried by the rear wall thereof and with the beer foam remover mounted upon the discharge end of the spigot;

Figure 2 is a fragmentary rear elevational view of the counter or bar showing the beer foam remover attached to the spigot and also carrying an upstanding bracket arm for the display of an advertising card or the like;

Figure 3 is a horizontal sectional view taken on line 3—3 of Figure 2; and

Figure 4 is a longitudinal sectional view taken on line 4—4 of Figure 3.

35 Referring more in detail to the accompanying drawing, the reference character 5 designates a counter or bar having a rear wall 6 through which projects a beer faucet 7 that is valve controlled as at 8.

40 The beer foam remover comprises a plate 9 of substantially triangular form in plan view as shown in Figure 3 with the tapered sides 11 thereof merging into one side of a ring 12 that carries an upstanding sleeve 13 intermediate the inner and outer edges of the ring as shown in Figures 3 and 4 to define a support 14 at the inner side of the lower end of the sleeve 13. The base edge of the triangular plate 9 is bent at right angles as shown in Figs. 2 and 4 to provide a scraper blade 15 depending from the plate 9. A cylindrical gasket 16 is confined within the sleeve 13 and rests at its lower end on the support 14 as shown in Fig. 4. The sleeve 13 is placed upon the lower end of the spigot 7 and is retained thereon by frictional engagement of the

gasket 16 with the spigot, the latter projecting below the plane of the plate 9.

When the valve 8 is opened to fill a glass with beer from the spigot 7, the glass may thereafter be laterally moved to cause the upper edge of the glass to move over the lower edge of the scraper blade 15 for removing excess foam from the glass of beer and said foam falls into the usual drain associated with dispensing apparatus of this character. The device is of a highly sanitary character, as it is unnecessary to touch the scraper blade 15 with the hands of the dispenser as contrasted with a usual blade or paddle that is customarily used and said device may be easily removed from the spigot 7 for a cleansing operation.

An advertising device is associated with the beer foam remover and includes a perpendicular rod 17 having an angularly offset lower end 18 that is received in a tubular support 19 rising from the ring 12 at the side thereof opposite the plate 9, the lower end 18 of the rod being bevelled as at 20 where seated in the tubular support 19 and engaged by a removable wedge key 21 for the rigid support of the rod on the ring 12. An advertising card 22 is connected to the upper end of the rod 17 that extends above the bar 5 by means of a nut and bolt combination 23 and such card may carry advertising for the particular kind of beer being dispensed. Slight movements of the plate 9 will follow contact of the upper edge of a glass with the scraper blade 15 and such vibrations will be imparted to the relatively long and thin rod 17 for attracting attention to the advertising card 22.

From the above detailed description of the invention, it is believed that the construction and operation thereof will at once be understood and while there is herein shown and described the preferred embodiment of the invention, it is nevertheless to be understood that minor changes may be made therein without departing from the spirit and scope of the invention as claimed.

45 I claim:—

1. In a beer foam remover, the combination with a spigot, of a plate having an opening in one end, a sleeve surrounding the opening and rising from the plate for mounting on the spigot, a scraper blade depending from the other end of the plate, a gasket interposed between the sleeve and spigot and the sleeve being spaced from the edge of the opening to provide a support for the lower end of the gasket.

2. In a beer foam remover, the combination with a spigot, of a plate having an opening in one end, a sleeve surrounding the opening and rising from the plate for mounting on the spigot,
5 a scraper blade depending from the other end of the plate, and a vertically extending rod supported on the plate and being of a length and dimensioned for vibratory movements when the scraper blade is used and an advertising card at the upper end of the rod.
10 3. In a beer foam remover, the combination with a spigot, of a plate having an opening in one end, a sleeve surrounding the opening and rising from the plate for mounting on the spigot,
15 a scraper blade depending from the other end of the plate, a gasket interposed between the sleeve and spigot and the sleeve being spaced from the edge of the opening to provide a support for the lower end of the gasket, and a vertically extending rod supported on the plate and being of a length and dimensioned for vibratory movements when the scraper blade is used and an advertising card at the upper end of the rod.
20 4. In a beer foam remover, the combination with a spigot, of a plate having an opening in one end, a sleeve surrounding the opening and rising from the plate for mounting on the spigot,
25 a scraper blade depending from the other end

of the plate, a vertically extending rod supported on the plate and being of a length and dimensioned for vibratory movements when the scraper blade is used and an advertising card at the upper end of the rod, the support for the 5 rod including a tubular socket rising from the plate, the lower end of the rod in the socket being tapered and a wedge key in the socket engaged with the tapered end of the rod.
10 5. In a beer foam remover, the combination with a spigot, of a plate having an opening in one end, a sleeve surrounding the opening and rising from the plate for mounting on the spigot,
15 a scraper blade depending from the other end of the plate, a gasket interposed between the sleeve and spigot and the sleeve being spaced from the edge of the opening to provide a support for the lower end of the gasket, a vertically extending rod supported on the plate and being of a length and dimensioned for vibratory movements when the scraper blade is used and an advertising card at the upper end of the rod, the support for the rod including a tubular socket rising from the plate, the lower end of the rod in the socket being tapered and a wedge key in the socket engaged with the tapered end of the rod.
